UNITED STATES PATENT OFFICE.

THEODORE WOZNEY, OF MILWAUKEE, WISCONSIN.

FLAT-CAR.

No. 847,716.

Specification of Letters Patent.

Patented March 19, 1907.

Application filed April 27, 1906. Serial No. 314,030.

To all whom it may concern:

Be it known that I, THEODORE WOZNEY, a citizen of the United States, residing at Milwaukee, in the county of Milwaukee and State of Wisconsin, have invented a new and useful Improvement in Flat-Cars, of which the following is a specification.

This invention relates to flat-cars, and more particularly to motor-operated dumping-cars, the object being to provide a car with very simple and effective means for tilting the platform in either direction desired.

Another object of my invention is to provide means for locking the platform on the truck so as to prevent all danger of the platform tilting accidentally.

The invention consists in certain details of construction hereinafter fully described, and pointed out in the claims.

In the drawings forming a part of this specification, Figure 1 is a side elevational view of the car. Fig. 2 is a top plan view of the car. Fig. 3 is a transverse sectional view of the car. Fig. 4 is a detail perspective view, partly in section, of the side sill of the car. Fig. 5 is a detail transverse sectional view of the side sills.

Referring to the drawings, A indicates a car mounted on trucks A', having side sills B, with enlarged central portions B' and flanged end portions B''. The extreme ends are bent at right angles, and the flange is split and bent outwardly, forming seats B''' for the end sills C, which are secured thereon by bolts passing through the flange B'' and the angle-plates D arranged thereon. The angle-plates D are provided with centrally-turned-down portions D', corresponding to the side sills, and between which beams D'' are secured, supporting a frame E. Cross-beams F are arranged on the angled plates D, provided with spaced brackets on their under side, in which shafts G are journaled, carrying arms H, provided with forked ends between which rollers H' are mounted. Gear-wheels I, provided with bifurcated collars I', are loosely mounted on the shafts G and mesh with worm-gears J', formed on a crank-shaft J, mounted in journals J'' on the frame E.

Grooved collars K, provided with lugs K', are keyed onto the shafts G adjacent the gear-wheels I and are adapted to be thrown into engagement with the collars G' by levers L, pivoted on the frame E, having their ends connected to a rod L', running longitudinally

of the car adjacent each side sill. A cylinder M is mounted on the frame E, provided with a pitman-rod M', connected to the crank-shaft J, and is adapted to be connected to the engine by a steam-pipe.

The side sills B and angle-plates D are provided with notches B', in which forked apertured lugs N are secured, adapted to receive the turned-down apertured ends O' of the cross-bars O, carrying the platform P and which are securely locked therein by pins. The cross-bars O are arranged over the arms H and are adapted to be engaged by the rollers H' when the shaft G is oscillated by the cylinder through the pitman-rod, gear-wheel, and worm-gear and tilt the platform. It is of course understood that the side of the platform to be raised is released by removing the pins out of the lugs and bars and that the clutch is thrown into engagement with the shaft on the same side. A chain Q, provided with jaws Q', is secured to each end of the car and is adapted to grip the truck and prevent the car from being turned over when unloading.

Having thus fully described my invention, what I claim as new, and desire to secure by Letters Patent, is—

1. In a flat-car, the combination with a platform, of means for pivoting said platform to either side of the car, arms pivoted under said platform and means connected to said arms for throwing the arms into engagement with said platform.

2. In a flat-car, the combination with a cross-bar carrying a platform, of means for pivoting said bars to said car, arms pivoted under said platform and means connected to said arm for throwing them into engagement with said cross-bars, for the purpose described.

3. In a flat-car, the combination with side sills, of cross-bars arranged on said sills carrying a platform, means for pivoting said cross-bars to said sills, arms arranged under said platform and means for throwing said arms into engagement with said cross-bars, for the purpose described.

4. In a flat-car, the combination with a detachable platform, of means for pivoting said platform to said car, shafts arranged under said platform provided with arms, gear-wheels mounted on said shafts, a crank-shaft provided with worm-gears, meshing with said gear-wheels, and an engine connected to said crank-shaft, for the purpose described.

5. In a flat-car, the combination with a platform, of means connected to said platform, for pivoting said platform to either side of the car, shafts arranged under said platform provided with arms, and means carried by said car for throwing said arm into engagement with said platform, for the purpose described. 25
6. In a flat-car, the combination with a platform adapted to be pivoted to either side of said car, of shafts arranged under said platform provided with arms carrying rollers at their ends, gear-wheels loosely mounted on said shafts, a crank-shaft provided with worm-gears meshing with said gear-wheels, an engine connected to said shaft, and means for locking said gear-wheels to said shaft, for the purpose described. 30
7. In a flat-car, the combination with the side sills, provided with bifurcated lugs, of a 35
- platform carried by cross-bars provided with turned-down apertured ends, means for pivoting said ends in said lugs, arms pivoted under said platform, and means connected to said arms, for throwing them into engagement with said platform, for the purpose described.
8. In a flat-car, the combination with side sills having notches formed therein, of forked lugs secured in said notches, cross-bars provided with turned-down apertured ends adapted to be pivotally mounted in said lugs, a platform carried by said cross-bars, arms arranged under said platform and means for throwing said arms into engagement with said cross-bars, for the purpose described. 30
